UNITED STATES PATENT OFFICE.

JACOB K. MOHLER, OF EPHRATA, PENNSYLVANIA.

HEATING-DRUM.

No. 800,002.

Specification of Letters Patent.

Patented Sept. 19, 1905.

Application filed November 26, 1904. Serial No. 234,326.

To all whom it may concern:

Be it known that I, JACOB K. MOHLER, a citizen of the United States, residing at Ephrata, in the county of Lancaster and State of Pennsylvania, have invented certain new and useful Improvements in Heating-Drums, of which the following is a specification, reference being had therein to the accompanying drawings.

This invention relates to improvements in that class of heating devices in which hot air or the products of combustion of a stove or furnace circulate around a cylinder through which passes a current of air to be heated; and the objects of these improvements are, first, to pass a heated current around said cylinder in a devious course, and, second, to so construct the drum that all the parts are held together by a single member, that the removal of said member may permit the separation of the parts.

The invention consists in the construction and combination of the various parts, as hereinafter fully described and then pointed out in the claims.

In the accompanying drawings, which form a part of this specification, Figure 1 is an elevation of a heating-drum embodying my invention; Fig. 2, a vertical section of the same; Fig. 3, an elevation of the drum, having part of the case cut away and showing the interior mechanism in full; Fig. 4, a horizontal section on broken line A A of Fig. 2; Fig. 5, a top view of the lower air-tubes and of the cone to which they are attached, the case being shown in section; Fig. 6, a plan view of one of the inner horizontal plates, and Fig. 7 a top plan view.

Similar numerals indicate like parts throughout the several views.

Referring to the details of the drawings, 1 indicates a cylindrical case or shell, and 2 the base of said case. Base 2 is formed with a rim 3, whereon are the feet 4, a cup forming the center thereof and having converging walls 5 with an annular opening 6 in its bottom, a depending rim or flange 7 around said opening, and a flange or rim 8 around the top of said converging walls, and in the converging walls are four circular openings surrounded by inwardly-projecting rims or flanges 9. The cap has a flat top 10, provided with an annular opening, around which is an upwardly-projecting flange or rim 11. The side wall 12 of the cap slopes downward and rests on the top of case 1, having a downwardly-curved rim 13, that projects beyond the side wall of said case, and in

side walls 12 are four circular openings having internally-disposed flanges 22.

In case 1 are two disk-like plates 14, having a central opening 15 and concentric openings 16 disposed around said central opening 15, and in and around opening 15 there is formed with each of the plates 14 a band 17, that projects both above and below the plate, forming an upper and a lower flange around opening 15. A cylindrical heat-flue 18 is located in the center of case 15, and it is surrounded by a helical blade 19, one end of which is bolted to the upper plate 14 and the other end to the lower plate 14, as shown, respectively, at 20 and 21. The lower end of heat-flue 18 rests on lower plate 14 and embraces the upper portion of its band 17, while the upper end of said flue embraces the lower portion of band 17 of upper plate 14, which upper plate rests on the heat-flue.

23 indicates an inverted hollow cone having around the upper edge annular shoulder 24, on the outer edge whereof is an upwardly-projecting flange 25, that embraces the lower edge of band 17 of lower plate 14, which rests on the upper edge of said flange 25, and in the conical wall are four circular openings 26, surrounded by outwardly-projecting flanges 27. The hollow cone 28, covering the heat-flue 18, is of similar construction, having an annular shoulder 29, that rests on the upper edge of band 17 of upper plate 14, and a flange 30, that embraces said band 17, and in the conical wall of this cone are circular openings 31, having outwardly-projecting flanges 32 in the same manner as with the lower cone. The flanges of the circular openings in the base, the cap, and the cones 23 and 28 are embraced by the ends of air-pipes 33, which are secured in position by tie rods or bolts 34 passing through the walls of the cones and the base and the cap, respectively.

In assembling the parts either one of the ends—the base or the cap—will first be put in its place on case 1. In this case the base, with the inverted cone 23 and the connecting air-pipes 33, is fitted to said case 1. The flue 18 is put in place. Then the plates 14, with the helical blade 19, are adjusted in position, after which the cap, with the upper cone 28 and the connecting air-pipes, is attached to the other parts of the drum. The parts are then all tightly bound together by a rod or bolt 35 passing through openings in the cones and through the heat-flue and secured at the lower end by a nut 36. The smoke-pipe is

engaged with the top flange 11 and the pipe from the stove or heater with the bottom flange 7, and it is through the openings surrounded by these flanges 7 and 11 that the rod 35 and nut 36 are put in place. As will be seen, the rod 35 is the only means by which the ends and the body of the drum are bound together, and when it is removed those parts can at once be separated for cleaning or repair.

In use the heat passes up through the opening surrounded by flange 7, and thence around and about the lower air-pipes 33, through the openings 16 in the lower plate 14, thence up through the winding channel formed by the helical blade 19, through the openings 16 in the upper plate 14, around and about the upper air-pipes 33, and thence out through the opening surrounded by the flange 11, thus subjecting the air to heat during its entire passage through said pipes 33 and through the flue 18. As is of course understood, air enters the drum through the lower pipes 33, rises through flue 18, and then passes out through upper pipes 33.

I do not restrict myself to the details of construction herein shown and described, as it is obvious that many alterations may be made therein without departing from the principle and scope of my invention.

Having thus described my invention, what I claim as new, and desire to secure by Letters Patent, is—

1. The combination, in a heating-drum, of the case thereof, a heat-flue in the case, a base and a cap on the ends of the case, a cone at each end of the heat-flue and having the base thereof in connection with the adjacent end of said heat-flue, air-pipes connecting open-

ings in said base and cap with openings in the adjacent cones, rods passing through the base and cap and the cones and securing those parts together, the base having an opening wherethrough the products of combustion pass into the space between the walls of the case and the walls of the heat-flue and the cap having an opening wherethrough said products of combustion pass from the drum, and a rod passing through the heat-flue and the apexes of the cones and removably connecting the base and the cap with the case.

2. The combination, in a heating-drum, of the case thereof, a heat-flue in the case, a base and a cap on the ends of the case, a cone at each end of the heat-flue and having the bases thereof in connection with the adjacent end of said heat-flue, perforated plates through which the heat-flue passes and bearing against the bases of said cones, a helical blade around the heat-flue between said plates, air-pipes connecting openings in said base and cap with openings in the adjacent cones, rods passing through the base and cap and the walls of the cones and securing those parts together, the base having an opening wherethrough the products of combustion pass into the space between the walls of the case and the walls of the heat-flue and the cap having an opening wherethrough said products of combustion pass from the drum, and a rod passing through the heat-flue and the apexes of the cones and removably connecting the base and the cap with the case.

JACOB K. MOHLER.
